UNITED STATES PATENT OFFICE.

EUGENE S. MANNY, OF MONTREAL, QUEBEC, CANADA.

STEAM-HEATING SYSTEM.

No. 836,391.

Specification of Letters Patent.

Patented Nov. 20, 1906.

Application filed July 24, 1905. Serial No. 270,942.

To all whom it may concern:

Be it known that I, EUGENE S. MANNY, a subject of the King of Great Britain, residing in the city and district of Montreal, in the 5 Province of Quebec, Canada, have invented certain new and useful Improvements in Steam-Heating Systems; and I do hereby declare that the following is a full, clear, and exact description of the invention, such as 10 will enable others skilled in the art to which it appertains to make and use the same.

This invention relates to new and useful improvements in heating systems and apparatus to be used in connection therewith:

15 The object of the invention is to provide means whereby tall buildings may be heated by means of a combination hot-water and steam system in which the water is heated by steam derived from a boiler properly located.

20 One of the great objections to the use of systems wherein water is heated by steam in tall buildings is that owing to the extreme length of the supply-pipes leading to the 25 radiators and the return-pipes leading therefrom too great a pressure is developed upon said pipes, which renders it practically impossible to use hot water for heating tall buildings.

30 The present system is designed for the purpose of relieving this pressure upon the pipes and comprises two or more zones of radiators arranged in different levels, each zone of radiators being supplied from a water-pressure 35 tank common to all of the radiators in a particular zone of radiators, but in no way connected with the radiators in the next higher or lower zone of radiators, there being means provided whereby the water flowing in each 40 zone of radiators may be heated, and the system includes means for shutting off the supply of steam to any individual vertical series of radiators in each zone when the water in that particular series is heated beyond a predetermined degree. Steam is taken from 45 boilers properly located and conducted into the couplings between the supply and return pipes of each vertical series of radiators for heating the water separately in each of said 50 series of radiators.

The invention consists in the combination and arrangement of parts which are shown in the accompanying drawings, all as herein-after more fully described, and particularly 55 pointed out in the claims, it being understood that said drawings illustrate the pre-

ferred construction, which may be departed from in the form, proportion, and minor details of parts therein shown within the scope of the claims without sacrificing any of the 60 advantages of the invention.

In the accompanying drawings, in which similar characters of reference indicate corresponding parts in all the views, Figure 1 is a sectional elevational view of a building 65 equipped with the present invention, the section being taken just back of the front wall of the building. Fig. 2 illustrates, partly in elevation and partly in vertical section, a single radiator of the system shown 70 in Fig. 1, with the improved heating-coupler which forms a part of this invention in proper position for use.

Referring to the parts, 1 indicates generally a steam-heating plant comprising firebox with boilers and a superheater from which extend the steam-pipes 2 and 3, through which steam-pipes the steam used for heating the water in the system is passed. 4 4 indicate radiators connected in vertical 80 series in the upper and lower zone of the building 5.

In the building illustrated herewith there are eleven stories above the cellar in which the steam-heating plant is located. The first 35 six stories comprise the lower zone of the system, and the radiators 4 of said lower zone are connected in vertical series; all in connection with the water-supply tank 6, and receive their water from said tank 6. 90 Supply-pipes 7, which are connected by means of a conduit 23 with said tank 6, are used to furnish water to said radiators, and return-pipes 8 carry the descending water from said radiators back to the supply-pipes 95 through couplings 9, for details of which reference is made to Fig. 2. This coupling 9 comprises an outer shell which may be provided with one or more tops, as may be desired, depending upon the number of pipes 100 which it is intended to connect therewith. Approximately centrally of the coupling 9 is a vertically-disposed partition 10, which is cast integral with the shell 9 and extends longitudinally of said coupling, but is shorter 105 than the coupling, so as to provide a passage (indicated by the arrow 11) at the lower end of said partition 10 and also provide a smaller passage (indicated by the arrow 12) at the upper end of said coupling, so that the major 110 portion of return water passing through the pipe 8 will find its way through the passage

115

11, while a small percentage thereof will pass through the passage 12.

Leading to the coupling 9 is a steam-pipe 13, and thereon is a valve 15, which is adapted to be actuated by movement of the diaphragm 16, which diaphragm is adjustably connected with the thermostat 17, which thermostat extends longitudinally of the chamber 14. In the chamber 18 of the coupling is supported a tube 19, which is closed at its upper end, and extending into the tube 19 is a steam-supply tube 20 in connection with the steam-pipe 13, with the valve 15 interposed between said members 13 and 20. In the operation of this coupling water will flow in the direction indicated by the arrows in Fig. 2 from the radiators 4 through the short connection 4^a to the pipe 8, thence through pipe 8 and the connection 8^a to the coupling 9. As steam is admitted to the interior of the tube 20 it will pass through the tube 19 and heat said tube 19, so that the water in the chambers 14 and 18 will be heated, the exhaust-steam discharging through the exhaust-pipe 21, which pipe leads to the pump 22, or otherwise, as may be desired.

It is evident that when water is heated in the chamber 18 the water will likewise be heated in chamber 14, and owing to the reduced area of the opening 12 the water will be retarded in the chamber 14 to some extent, so that the passage thereof will be somewhat sluggish and will raise the temperature of the thermostat 17 according to the temperature of the water in the chamber 14. When enough of the radiators 4 in any of the vertical series are cut off, the temperature will be raised to such degree that the thermostat will actuate the diaphragm 16 and through said diaphragm close the valve 15, thereby cutting off more or less steam to the couplings 9.

The vertical series of radiators are indicated in Fig. 1 in the lower zone respectively as A B C D E. Each series has a separate steam-supply pipe 13 leading to the coupling 9 of said series, and it is evident that one or more of said series from A to E may be cut off entirely without interfering with the operation of the remaining series. As the main 23, leading from the tank 6, is connected to each of the series from A to E, inclusive, and well-known means are provided for maintaining a constant supply of water in said tank, it is evident that the necessary quantity of water will be supplied to the radiators of said series, and owing to the short length of the supply and return pipes 7 and 8 there will be relatively little pressure developed in said pipes.

The upper zone of the building is provided with series of radiators lettered, respectively,

F, G, H, I, and J, the series from F to J being substantially duplicates of the lower series from A to E, inclusive, and a second water-pressure tank 6^a is provided in the upper zone of the building, which is connected by means of the main 23^a with the said series of radiators from F to J. The supply and return pipes 7 and 8 of the upper series are provided with couplings 9, as in the lower series, and the radiators 4 of said upper series are arranged in vertical series, as shown and substantially as described. With reference to the lower zone of the building the steam-pipe 3 leads to the couplings 9 of the upper zone, so that the water is heated in the upper zone of the building from said steam-pipe 3, each zone having an independent water-pressure tank and independent live-steam connections, so that each zone of the building may be operated independently of the other zone or zones thereof and the pressure be kept down in all of the water-pipes of the system.

Having described my invention, what I claim, and desire to secure by Letters Patent, is—

1. In a heating system for heating water with steam, a supply-pipe, a radiator, a return-pipe and a coupling for said pipes, said coupling comprising an outer shell, with a partition approximately centrally of said shell but of less length so as to leave a water-passage at each end thereof, a closed tube on one side of said partition, a steam-pipe extending nearly the length of and within said tube, and a thermostat on the opposite side of said partition said thermostat being adapted to control the flow of steam through said steam-pipe.

2. In a heating system for heating water with steam, a supply-pipe, a radiator, a return-pipe and a coupling for said pipes, said coupling comprising an outer shell with a partition approximately centrally of said shell but of less length so as to leave a water-passage at each end thereof, said passages differing in size, and the smaller passage being at the upper end of said partition, a closed tube on one side of said partition, a steam-pipe extending nearly the length of and within said tube, and a thermostat on the opposite side of said partition said thermostat being adapted to control the flow of steam through said steam-pipe.

In witness whereof I have hereunto set my hand in the presence of two witnesses.

EUGENE S. MANNY.
